UNITED STATES PATENT OFFICE.

BENJAMIN F. THOMAS, OF SURPRISE, NEBRASKA.

COTTER-PIN TOOL.

Application filed February 23, 1927. Serial No. 170,256.

My invention relates to cotter pin tools and its primary object is the provision of a tool for pulling cotter pins, the tool having interfitting jaws which so engage each other 5 that the tool may be freely manipulated without danger of the jaws opening and releasing the cotter pin. Especially is it my object to provide a jaw arrangement for a cotter pin puller whereby cotter pins in the most inaccessible places may be grasped and pulled. Incidentally it is my object to provide handle ends for the tool which are especially adapted for straightening out cotter pins which have become bent and to provide wire cutting jaws 10 for cutting cotter pins which require cutting.

Having in view these objects and others which will be pointed out in the following description, I will now refer to the drawings, in which

20 Figure 1 is a side view of the entire cotter pin tool.

Figure 1^A is a similar view of the jaw portion only of the cotter pin tool showing the jaws in their closed position.

25 Figure 2 is an edge view of the cotter pin tool.

Figure 3 is an end view of the cotter pin tool.

30 Figure 4 is an illustration showing the cotter pin tool in engagement through the eye of a cotter pin.

The tool includes two pivoted portions which are secured together by means of a pivot pin 10 as in pliers. While the figures show 35 my preferred construction, it is obvious that any construction embodying two pivotally connected crossed arms will serve the purpose and I therefore wish it to be expressly understood that I do not limit myself to the particular form of pivotally connected crossed arms shown in my drawings.

The pivotally connected crossed arms which I show are provided with wire cutting portions 11 for convenience in cutting cotter pins and with tapering pointed ends 12 which are useful as levers in straightening out bent and twisted cotter pins.

50 The main feature of the invention, however, resides in the interfitting jaws 13 and 14. The male jaw 13 tapers bluntly and the female jaw 14 is provided with a socket for re-

ceiving the joint of the jaw 13. As shown in Figure 1^A, these jaws interfit in such a manner that their exterior surfaces are smooth and continuous and the center lines or longitudinal axes of the conical surfaces are 55 in alignment.

The use of the tool is partially shown in Figure 4. Regardless of the position in which the cotter pin is found the head of the tool 60 is small enough so that the tool may be readily caused to engage through the eye of a cotter pin. The pull may then be along the axial line of the tool, but in some inaccessible places it will be necessary to turn the tool 65 through an angle and then to pull the cotter pin with its eye engaging one or the other of the two jaws. The tool cannot slip because the harder the pull on the tool, the harder 70 the grip on the handles and consequently the harder the engagement between the jaws 13 and 14.

Having thus described my invention in such full, clear, and exact terms that its construction and operation will be readily understood by others skilled in the art to which it pertains, what I claim as new and desire to secure by Letters Patent of the United States is:

A cotter pin puller comprising a pair of 80 pivotally connected crossed arms, said arms terminating respectively in curved interfitting male and female jaw members, the extremity of said male jaw member being conical in form and the free end of said female jaw member being provided with a conical socket for snugly receiving the conical portion of said male jaw member in a manner such that the exterior surfaces and the longitudinal axes of said jaw members are each 85 continuous when said male and female jaw portions are in their interfitting position, said jaw members being adapted to engage the eye of a cotter pin in nonclamping relation whereby said cotter pin puller may be turned to any 90 desired angular position with respect to the cotter pin so that either of said jaw members may function as a rolling fulcrum when pulling the cotter pin.

In testimony whereof I affix my signature.

BENJAMIN F. THOMAS.
